UNITED STATES PATENT OFFICE.

CHARLES F. SPLITDORF, OF NEW YORK, N. Y.

CONDENSER.

SPECIFICATION forming part of Letters Patent No. 728,780, dated May 19, 1903.

Application filed August 4, 1902. Serial No. 118,230. (No model.)

To all whom it may concern:

Be it known that I, CHARLES FREDERICK SPLITDORF, a citizen of the United States, residing in the borough of Manhattan, city, county, and State of New York, have invented a new and useful Improvement in Condensers, of which the following is a specification.

This invention relates to condensers for induction-coils in general, although it is intended by me to be used primarily in conjunction with coils of the jump-spark order, its characteristics being a compact circular form, enabling its inclosure adjacent to a coil within a common cylindrical casing, together with a special facility and economy of manufacture not hitherto attainable.

In brief, my improvement consists in forming into a roll a series of superimposed strips which are alternately positive and negative condenser elements and are composed, as is usual, of tin-foil or the like. Between each pair of such strips is interposed an insulating-strip of paper or other dielectric, these latter having a relatively greater width to extend beyond the side edges of the condenser strips, and thereby properly insulate the positive and negative elements from each other. Lengthwise the arrangement of the metal and paper strips is such that corresponding ends of all the positive metal strips project beyond the paper and are in electrical connection, and the opposite ends of the negative metal strips likewise project beyond the paper strips and are in electrical connection. Thus one end of the series of strips is composed of contacting laminae of positive sign, while the opposite end of the series is composed of contacting laminae of negative sign. The laminae at one end, as the positive, are initially wrapped about a terminal, as a wire or metal rod, being either soldered or otherwise securely attached thereto. The whole laminated bundle, comprising the positive and negative strips and the intermediate dielectric strips, is then wound tightly and compactly upon itself in convolute form about the terminal core to produce a roll of a desired thickness, according to the length of the strips employed. The respective outer ends of the negative strips, although conterminous when spread at length, are fanned out in the

act of forming the roll, and I am therefore enabled to make contact with each one by means of a wire or metallic strip which I now 55 wind tightly around the roll, binding it together, the said strand thereby forming the opposite terminal of the condenser.

In the drawings accompanying this application, Figure 1 is a plan perspective view of 60 the condenser elements prior to their being rolled into finished form. Fig. 2 is a longitudinal section through the line 2 2 of Fig. 1. Fig. 3 is a cross-section of the condenser, and Fig. 4 is a front view thereof.

In the figures the letter A indicates one of the condenser-terminals, as, we will say, that of positive sign, and B indicates each of the metallic strips, also of positive sign, whose corresponding ends are connected, as at b, 70 while the main body of the series is interleaved in succession with strips of insulating paper, as C or the like, and with other like metallic strips, as D. The ends of the positive metallic strips where connected, as at b, 75 are wrapped about the terminal A, to which latter they are preferably secured, as by soldering, to prevent displacement and effect close electrical union therewith. The whole bundle of strips which are arranged in the 80 order of the lowermost negative metallic strip then in succession an insulating paper strip, a positive metallic strip, and an insulating-strip. This series being repeated to comprise a condenser of the required capacity is then 85 wound upon the core and itself in convolute form. It will be observed that whereas the insulating paper strips do not cover the ends of the metallic strips B at b they do cover and inclose the corresponding ends of the 90 metallic strips D, which are of negative sign. Hence connection between the strips B and D is avoided at this point and efficient insulation provided. At the opposite end of the bundle the strips B lie short within the insulating paper strips C, being covered thereby, while the ends of the negative metallic strips 95 D project, as at d, and are in contact with each other. When the bundle has been rolled up completely, it will be found that the strips 100 D, which were of equal length, have been fanned out at d in the process of forming the roll, so that as said strips lie upon the roll a small end portion of each one is exposed. I

now bind the roll tightly together with a wire or other metal strand or strip, as E, winding the latter several times around the roll, whereby it is brought snugly in connection with 5 the exposed edges of each of the metallic negative strips D, and thus forming a terminal for the negative series.

Suitable portions of the respective terminals A and E may project for connection with 10 an electrical circuit, as is obvious.

I claim—

A condenser composed of a bundle of alternately-disposed metallic and dielectric strips, said metallic strips being alternately 15 of positive and negative sign, one set of elements, as the positive, being free at one end and wrapped about a terminal, said terminal

forming a core, and the other set of elements as the negative, being free at the opposite end, the whole of said bundle, being rolled 20 upon itself, exposing the end edges of each of the negative strips; together with a negative terminal in the form of a wire or metallic strand wound about the roll in contact with the exposed negative-strip edges and serving 25 to bind the roll together.

In testimony whereof I have signed my name to this specification in the presence of two subscribing witnesses.

C. F. SPLITDORF.
